UNITED STATES PATENT OFFICE

145,867

DESIGN FOR A HOLDER FOR FLOWERS OR OTHER SLENDER ARTICLES

Frank P. Fletcher, Pasadena, Calif.

Application August 1, 1945, Serial No. 121,141

Term of patent 14 years

(Cl. D35—3)

To all whom it may concern:

Be it known that I, Frank P. Fletcher, a citizen of the United States, residing at Pasadena, in the county of Los Angeles and State of California, have invented a new, original, and ornamental Design for a Holder for Flowers or Other Slender Articles, of which the following is a specification, reference being had to the accompanying drawing, forming part thereof.

Fig. 1 is a perspective view of a holder for flowers or other slender articles, illustrating my new design;

Fig. 2 is a side elevational view thereof;

Fig. 3 is a top plan view thereof;

Fig. 4 is an end elevational view thereof;

Fig. 5 is another end elevational view thereof and is taken in a direction opposite to that of Fig. 4; and

Fig. 6 is a bottom plan view thereof.

I claim:

The ornamental design for a holder for flowers or other slender articles, as shown.

FRANK P. FLETCHER.
